By his Attorneys,

Inventor

Lorin P. Riddle

C. A. Snow & Co.

UNITED STATES PATENT OFFICE.

LORIN PATTERSON RIDDLE, OF ASHLAND, OHIO.

BLACKBOARD-ERASER.

SPECIFICATION forming part of Letters Patent No. 416,184, dated December 3, 1889.

Application filed September 11, 1889. Serial No. 323,585. (No model.)

To all whom it may concern:

Be it known that I, LORIN PATTERSON RID-
DLE, a citizen of the United States, residing at
Ashland, in the county of Ashland and State
of Ohio, have invented a new and useful Black-
board-Eraser, of which the following is a speci-
fication.

This invention has relation to blackboard-
erasers of that class employing felt and other
suitable substances, and among the objects in
view are to provide an eraser so arranged as
to produce a series of drafts through the
same induced by the movement of the eraser
while passing over the board, whereby the
10 crayon-dust is lifted from the board by the
eraser and retained therein, and thus the sur-
face of the board can always be efficiently
cleaned.

With these general objects in view the in-
vention consists in an eraser having a series of
longitudinal and transverse channels formed
in its erasing-face by a series of blocks of felt
placed at equal distances apart.

Referring to the drawings, Figure 1 is a
25 perspective of an eraser constructed in ac-
cordance with my invention; Fig. 2, a detail
in perspective of one of the felt blocks.

Like numerals of reference indicate like
parts in all the figures of the drawings.
30 1 represents the usual back of the eraser,
preferably formed of suitable wood, and 2
the eraser-surface, preferably formed of felt
and provided with a series of longitudinal
grooves 3 and transverse grooves 4. In my
35 present invention I form these grooves by
pasting upon the surface of the back a series
of uniformly-arranged rows of independent
square or, it may be, other shaped felt blocks
5, each block being isolated from the adjacent

blocks, and thereby forming the grooves or 40
recesses described. If desired, these blocks
may be of diamond shape, whereby the grooves
will be diagonal and at acute and obtuse an-
gles to each other. If desired, also, the blocks
may be formed integral—that is, pressed by 45
suitable dies—so as to have a backing of felt,
which backing is integral with the blocks; or
said blocks may be pasted to a suitable back-
ing of fabric material and the backing pasted
to the face of the back of the brush; but for 50
obvious reasons I prefer the construction de-
scribed.

Having described my invention, what I
claim is—

1. An eraser for the purpose described, hav- 55
ing a series of grooves crossing each other
formed in its face, substantially as specified.

2. An eraser for the purpose described, the
back of which is provided with a series of
angular felt blocks secured thereto in regular 60
rows and isolated from each other to form a
series of intermediate longitudinal and trans-
verse grooves, substantially as specified.

3. An eraser for the purpose specified, the
back of which is provided with a series of in- 65
dependent blocks formed of felt and glued
thereto, and arranged in regular rows and
isolated from each other to form intermediate
draft-inducing open-edged spaces extending
throughout the length and breadth of the 70
back, substantially as specified.

In testimony that I claim the foregoing as
my own I have hereto affixed my signature in
presence of two witnesses.

LORIN PATTERSON RIDDE.
